UNITED STATES PATENT OFFICE.

FRANK L. SCHNEIDER, OF SHELLROCK, IOWA.

BARREL-LIFTER.

1,379,313.

Specification of Letters Patent. Patented May 24, 1921.

Application filed October 14, 1920. Serial No. 416,819.

To all whom it may concern:

Be it known that I, FRANK L. SCHNEIDER, a citizen of the United States, residing at Shellrock, in the county of Butler and State 5 of Iowa, have invented certain new and useful Improvements in Barrel - Lifters, of which the following is a specification.

This invention relates to improvements in supports especially adapted for use in 10 connection with water barrels and the like.

An important object of the invention is to provide a support of the class described having novel means whereby a barrel filled with water or other liquid may be elevated 15 to a point at which it is convenient to dispense the water or other liquid.

A further object of the invention is to provide a support or lifting apparatus of the class described having simple means for 20 securing the barrel against movement when in an elevated position.

A further object of the invention is to provide an apparatus of the class described which is of highly simplified construction, 25 efficient in use and cheap to manufacture.

Other objects and advantages of the invention will be apparent during the course of the following description.

In the accompanying drawing forming a 30 part of this application and in which like numerals are employed to designate like parts throughout the same:

Figure 1 is a side elevation of the improved barrel lifting apparatus;

Fig. 2 is a front elevation of the same, parts being shown in section.

In the accompanying drawing, wherein for the purpose of illustration is shown a preferred embodiment of the invention, the 40 numerals 10 designate standards which converge in the direction of their upper ends and which are connected by means of a bolt 12 having threaded engagement with a nut 14. As illustrated in Fig. 2, a sleeve 45 16 is mounted on the bolt 12 between the upper end portions of the standards 10 and serves as a means for bracing the same with relation to each other.

The standards 10 are mounted on the base 50 members 20 which may be of angle iron and which are secured to the lower portions of the standards by means of bolts 22. The end portions of the base members are connected to the standards by means of bracing 55 rods 24 secured to the standards by means of bolts or other fastening devices 26.

A drum 30 is rotatably extended through the upper portions of the standards and has a rope or other flexible element 32 secured thereto so that as the drum rotates, 60 the flexible element 32 will be wound upon the same. The drum 30 is provided with an operating handle 34 by means of which the drum may be manually rotated.

The drum may be secured in an adjusted 65 position by means of a pivoted pawl 38 which co-operates with a ratchet wheel 40 keyed or otherwise secured to the drum. In this manner, the flexible element and the drum 30 may be employed for securing a 70 barrel 42 or other object in an elevated position.

With reference to Fig. 1, it will be noted that the lower portion of the flexible element 32 is formed with a loop 43 which 75 slidably receives a flexible element 44 in the form of a chain. One end portion of the chain is permanently connected to a hook 46 while the other end of the chain is passed through an opening in the rear portion of a barrel-engaging hook 48. The last-mentioned end portion of the chain is provided at its end with a hook 50 adapted to selectively engage any one of the links of the chain so that the effective length of the 80 chain may be varied at will. In this manner, the chain and the hooks 46 and 48 may be employed for supporting barrels of various lengths. Since the flexible element 44 is slidable through the loop 43, equal portions of the chain may be arranged on opposite sides of the loop after the length of the chain has been adjusted for use in supporting a barrel of a particular length.

In the use of the improved barrel elevating apparatus, the barrel is positioned between the standards 10 and the hooks 46 and 48 are subsequently engaged with the chines of the barrel. The drum 30 may now be rotated by a corresponding movement of the handle 34 so as to wind the flexible element 32 onto the drum whereby the barrel will be elevated. The elevation of the barrel continues until the sides of the same are firmly engaged with the adjacent portions of the standards. Since the standards gradually converge in the direction of their upper ends, barrels of various widths may be securely held in position. The drum may be held in a set position for 100 securing the barrel in position by means of the pawl and ratchet 38 and 40 respectively. 105 110

When thus held securely in an elevated position, the contents of the barrel may be dispensed through a spigot 52.

Having thus described the invention, what 5 is claimed as new is:

A lifting device for barrels comprising a pair of inclined standards, spacing means connecting the upper ends of the standards, a drum carried by said standards, means 10 whereby the drum may be secured in a set position, base members each secured midway its ends to the lower end of a standard, braces secured to said base members and the adjacent standards, a flexible element wound

about and secured to said drum, said flexible element being provided at its lower end with a loop, a chain passed through said loop, a barrel engaging hook carried by one end of said chain, a second barrel-engaging hook having an opening slidably receiving 20 said chain, and a holding member carried by the slidably received end of the chain and adapted for engaging the links of the chain whereby the effective length of the chain may be varied. 25

In testimony whereof I affix my signature.

FRANK L. SCHNEIDER. [L.s.]
